UNITED STATES PATENT OFFICE.

CLYDE R. HARDING, OF COUNCIL BLUFFS, IOWA.

FLYING HORSE.

Application filed May 5, 1927. Serial No. 189,153.

My invention relates to swings and one of its objects is the provision of a swing which is driven forward by the weight of the driver acting on stirrups. Another of 5 its objects is the provision of features which make the swing absolutely safe even when operated by the most careless and reckless children. A third object is the provision of mechanical means for supplementing the 10 action of gravity and thus causing the swing to move backwardly on the return movement. Still another object is the provision of a swing which will appeal to children because of its attractiveness and which will 15 appeal to playground supervisors because of its safety.

Having in view these objects and others which will be pointed out in the following description, I will now refer to the drawings, in which—

20 Figure 1 is an illustration of the entire swing with parts broken away to disclose certain interior constructions which would otherwise be hidden.

25 Figure 2 is a diagrammatic view of the swing and its linkage, the position at rest being shown in whole lines and the forward position of the swing with its linkage being shown in dotted lines.

30 The seat of the swing, which in the present instance is in the form of a horse, is formed of three layers, the middle layer being cut away in the body of the horse to provide space for the lever mechanism. In 35 the top portion between the inner and outer layers is a heavy casting 10 which is bolted or otherwise rigidly secured to the layers on the opposite sides of the horse. This casting gives rigidity to the seat and it furnishes a base for the operating mechanism.

40 It is provided well forward of the center line of mass with an upstanding socket member 11 which is screw threaded on its interior. The tubular member 12 is fitted into

45 the socket and is pivotally secured at 13 to any suitable support such as 14. In the present instance I employ a casting 15 which is rigidly secured to the support 14 and which is provided with depending aper-

50 tured ears for receiving the tube 12 and its pivot. Thus far the swing is merely the ordinary swing except that the seat is suspended in such a manner that the rider will tilt it forwardly as soon as he occupies the 55 seat.

Inside the seat body is a bent lever 16

which is pivotally connected at 17 to the casting 10 and which extends first rearwardly and then forwardly and downwardly, terminating in the stirrups 18. 60 The spring 19 extends from a point in the lower portion of the bent lever 16 to a point at or near the rear extremity of the casting 10. Pivotally connected to the lever 16 at 20 is a rod or bar 21 passing through the 65 tubular member 12. The upper end of the rod or bar 21 is connected to one arm of the angular lever 22. The tubular member 12 is slotted on its rear side to permit the up and down movement of the forward arm 70 of the lever 22. The lever 22 is pivotally secured to the link 23 which in turn is pivotally secured to the clamp 24 surrounding the tubular member 12. It is obvious 75 that the up and down movement of the stirrups 18 will be communicated through the rod 21 to the lever 22.

The casting 15 is provided with a projection to which is secured a support 25, the support extending rigidly in an upward 80 and rearward direction. In the present instance the support 25 consists of a pair of bars of channeled steel or the like which converge toward the rear end of the support. Pivotally secured to the support 25 at 26 and 85 27 is a lazy tongs lever having pivots 28, 29 and 30, the pivot 30 being on a curved link 31 which is pivotally connected to a clamp 32 surrounding the tubular member 12. The limbs of the lazy tongs lever progressively 90 decrease in length from its upper end. The lever 22 is connected by means of a link 33 with the lazy tongs lever at the pivot 29, the link 33 being connected to the lever 32 by means of the pivot 34. For the sake 95 of rigidity the lower end of the lever 22 is bifurcated and is made to straddle the link 31 and the link 33 is double and straddles the lower portion of the lazy tongs lever.

In operation the rider seats himself on the 100 horse which is provided with a suitable saddle. He then presses down with his feet in the stirrups 18. This, of course, exerts a downward force on the rod 21 and on the forward end of the angular lever 22. This force is communicated through the pivot 34 and through the link 33 against the point 29 of the lazy tongs lever. It should, however, be noted that the pivotal points 27, 28, 29 and 30 are in alignment and that the points 29 and 34 are out of alignment with the 105 pivotal points of the lazy tongs lever. As 110

soon as this force is exerted in a direction which is out of alignment with the pivots of the lazy tongs lever, the point 29 serves as an abutment in the initial movement caused by the actuation of the stirrups 18. The force is thus reacted through the link 23 and in a forward direction against the tubular member 12. The rod 21 cannot move downwardly except as the lower end of the tubular member 12 moves forwardly.

The swing is driven forward by the downward pressure of the feet in the stirrups 18 and the driver is thus enabled to exert the pressure of his entire weight in driving the swing forward. He may supplement this action by the movement of his body as in the ordinary swing but the fact that the primary movement is downward and in a vertical direction makes it possible to actuate the swing with the least possible effort. The driver is enabled to apply his full weight by temporarily standing in the stirrups but in the initial movement he also has the advantage of the leverage in his legs. During the forward movement of the swing the spring 19 is lengthened and thus tensioned so that on the return movement the spring will hasten the rearward action toward a vertical position of the swing, the remainder of the rearward movement being the ordinary pendulum movement which has been intensified by the spring 19.

The main part of the actuating mechanism is considerably overhead the driver's position and is thus out of reach of children. The tubular support 12 is smooth and children find it difficult and almost impossible to climb to the linkage. The children can therefore not be injured with broken fingers or limbs by getting them entangled in the operating linkage. The lever 16 is entirely inside the body of the horse and is inaccessible to children. It should also be noted that the essential part of the swing seat is the casting 10 which is heavy and rigid enough to withstand the strains which are due to the action of boisterous children. The body of the horse is utilized for two reasons. Its form appeals to children but the main reason for its use is the fact that its sides enclose the lever 16 and the spring 19. It is possible of course to obtain the latter result by the use of a body simulating any other animal, as for example an elephant or an ostrich.

Having thus described my invention in such full, clear, and exact terms that its construction and operation will be readily understood by others skilled in the art to which it pertains, what I claim as new and desire to secure by Letters Patent of the United States is:

1. A swing including a seat rigidly secured to a depending tubular member, said tubular member being adapted to be pivotally se-

cured at its upper extremity to an overhead support, an operating linkage secured to said tubular member and to an overhead support at points remote from said tubular member, and foot actuated means for imparting movement to said operating linkage for propelling said swing, said means being inside said tubular member and connected at its upper extremity to said operating linkage and at its lower extremity to a stirrup below said seat and said tubular member.

2. A swing including an overhead support, a rigid tubular depending member pivotally secured to said support, a lazy tongs linkage secured at its upper extremity, said support rearwardly of said depending member to and secured at its lower extremity to said depending member at an intermediate point thereof, a seat secured to said depending member at the lower extremity thereof, a lever pivotally connected to said seat and depending therefrom and terminating in stirrups, a link connected to said lever and being positioned inside said tubular depending member and projecting downwardly and outwardly therefrom, and a connection between said linkage and said link whereby downward pressure of said stirrups will impel said swing in a forward direction.

3. A swing including a seat member, a lever pivotally secured to said seat member, said lever being positioned beneath said seat member and projecting rearwardly and downwardly from the pivotal connection thereof, a tubular swing-supporting member secured to said seat member and projecting upwardly therefrom and adapted to be secured at its upper extremity to an overhead support, said tubular member being provided with an aperture in the side thereof, and a flexible swing-actuating mechanism secured at its lower extremity to said lever and passing upwardly through said seat member and through said tubular member and passing outwardly through the aperture in said tubular member, said swing-actuating mechanism being adapted to be secured at its upper extremity to an overhead support at points remote from said tubular member.

4. A swing including a seat member, a lever pivotally secured to said seat member, said lever being positioned beneath said seat member and projecting first rearwardly and then downwardly from the pivotal connection thereof, a tubular member secured to said seat member and projecting upwardly therefrom and adapted to be secured at its upper extremity to an overhead support, said tubular member being provided with an aperture at the side thereof, a link slidable in said tubular member and pivotally secured at its lower extremity to said lever, and an operating member secured at its lower extremity to said link and projecting outwardly and upwardly through the aperture in said

tubular member and adapted to be secured to an overhead support at points spaced from said tubular member.

5. A swing including a seat member, a lever pivotally secured to said seat member on the under side thereof and projecting rearwardly and downwardly and terminating in stirrups at the lower extremity thereof, a tubular swing-supporting member secured to said seat member to project upwardly therefrom and adapted to be secured at its upper extremity to an overhead support, a lazy tongs linkage secured to said tubular member intermediate the extremities

thereof and projecting upwardly and rearwardly therefrom and adapted to be secured at its upper extremity to an overhead support at points rearwardly from said tubular support said tubular support being provided with an aperture intermediate the extremities thereof for receiving the lower end portion of said lazy tongs linkage, and a connecting member between said lever and said lazy tongs linkage, said connecting member passing through said seat member and said tubular member. 15
